SEWING MACHINE LOOP SHAPER ATTACHMENT

Abraham Gellman, New York, and Sidney Diesenhaus, Monsey, N. Y.

Application November 16, 1951, Serial No. 256,797

2 Claims. (Cl. 223—110)

This invention relates to a loop shaper preparatory to placing the loop on a folded hem of a parachute or other goods' surface requiring a loop for uniform affixation thereto of a retaining loop.

It is an object of the present invention to provide a loop shaper on which a loop of strap material can be made preparatory to the placing of the same upon the hem and in position for a stitching operation to secure the loop to the hem.

It is another object of the invention to provide a device on which a loop strap can be applied to shape the loop and wherein by the same device the strap can be placed on the hem in the proper location and the side ends of the strap properly aligned to the desired angle as indicated by the shape of the bottom plate and whereby all loops will be applied in a uniform manner and of uniform shape upon the hem of a parachute or on a preselected surface portion of other goods requiring affixation of retaining loops so that all loops are alike in size and are evenly distributed.

It is another object of the invention to provide a loop forming device on which the loop will be shaped and placed by means of the device upon the hem or object to be applied and wherein the device is so constructed that an opening in the foot of the sewing machine serves as a guide for applying the device with the loop thereon upon the hem or surface. The heel of the claw also serves to hold the loop in place and the arms of the foot hold the arms of the strap when the foot or claw of the sewing machine is brought down. The device is withdrawn or removed from the loop and arms of the strap prior to the beginning of the stitching operation as will hereinafter appear.

It is another object of the invention to provide on a loop forming and applying device a centering guide member which is adjustable relative to the base plate part of the device and adapted to enter between the claws or arms of the sewing machine foot so that the sewing machine foot acts as a guide when using this device to properly locate the loop upon the hem and for the beginning of the stitching operation and wherein the loop will be properly and automatically located on the hem in the proper position to receive the stitching needle when the device has been taken away.

Other objects of the invention are to provide a loop forming device having the above objects in mind, which is of simple construction, inexpensive to manufacture, has a minimum number of parts, adjustable, compact and efficient in operation.

For a better understanding of the invention, reference may be had to the following detailed description taken in connection with the accompanying drawings, in which:

Fig. 1 is a perspective view of the loop forming device embodying the features of the present invention;

Fig. 2 is a collective and perspective view of the several parts of the device;

Fig. 3 is a longitudinal sectional view of the device taken on line 3—3 of Fig. 1;

2

Fig. 4 is a perspective view of the strap from which the loop is made;

Fig. 5 is a perspective view of the device and of the strap being applied to the device;

Fig. 6 is a perspective view of the device and of the hem of a parachute or other device to which the loop is to be applied and with illustration made of the foot, or claw, of the sewing machine in place over the loop to hold it while the device is pulled rearwardly, whereby to permit the stitching operation to be effected upon the strap;

Fig. 7 is a top plan view of the loop already stitched and applied to the hem of the parachute or other device.

Referring now to the figures, 10 represents a base member having wing portions 11 and 12 with inclined edges 13 and 14 respectively. Extending forwardly from the wing portions is a tapered projection 15 over which the strap 16 from which the loop is made is folded. This strap 16 is extended along one edge of the one wing portion to assume the angle thereof and is brought around, as shown in Fig. 5, to shape the loop and thereafter the other end of the strap is brought along the inclined edge of the other wing portion, in a manner as shown in Fig. 6. The strap 16 has inclined end edges 17 and 18 which will extend parallel to hem 19 of a parachute 20 or other surface of any other device requiring retaining loops.

The rear end of the bottom plate 10 is bent upwardly at 21 to provide a handle in which there is disposed a single finger opening 22 that can be used in the manner as illustrated in Fig. 6.

Fixed to the bottom plate 10 by means of screws 23 and 24 is a transversely extending block piece 25 having a large threaded hole 26 and two smaller threaded holes 27 and 28 on the respective opposite ends thereof.

A spring finger 32 extends under the block piece 25 and within a groove 29 on the bottom thereof and is held by a screw 31 within the large hole 26. This spring finger 32 extends outwardly over the bottom plate and onto the tapered portion 15 at the end thereof. The screws 23 and 24 respectively enter holes 27 and 28 to hold the block piece in place. Holes 34 and 33 are provided in the bottom plate to receive the screws 23 and 24, Fig. 2.

A long angle piece 35 is rested over the block 25 and its vertical edge has a recess 36 to permit the spring finger 32 to pass outwardly thereunder. This angle piece 35 carries an adjustable pointed guide member 41 and has a transversely extending portion 42 with overlying spaced horizontal portions 43 and 44 having respectively elongated slots 45 and 46. Screws 47 and 48 respectively extend through the slots for connection with the respective threaded holes 37 and 38 in the angle piece 35.

Screws 51 and 52 having respectively washers 53 and 54, extend downwardly respectively through elongated slots 39 and 40 of the angle piece 35 and into holes 55 and 56 of the block piece 25.

It will thus be seen that longitudinal adjustment of the guide member 41 along the finger spring 32 can be effected by loosening the screws 51 and 52 and pulling the angle piece 35 forwardly or pushing it rearwardly. The guide member 41 can be adjusted laterally on the angle piece 35 by loosening screws 47 and 48 and sliding the same along the top face of the angle piece 35.

In operation, the strap 16 is wrapped about the tapered end 15 of the bottom plate in a manner as shown in Figs. 5 and 6. The strap sides will be brought into alignment with the inclined edges 13 and 14 of bottom plate 10, to be given the proper angle and to give the proper shape to the loop which is being formed. The device with the strap thereon is then placed on the hem 19, as shown in Fig. 6 beneath the sewing machine so that claw or foot 58 with separated claw portions angled apart receives the pointed guide member 41. The opening in foot 58 may have a different shape to accommodate re-

ception of member 11 of different shape. Since the folded loop strap is temporarily retained by the finger 32, the claw portions will lie outside both of the spring finger 32 and the guide member 41 when the claw is brought down to bear directly on the loop. By pulling the device outwardly while foot 58 is down on the loop which is aligned with the hem 19, the stitching operation can be started with needle 59. The initial stitching on loop 61 is indicated at 60, Fig. 7, and will continue downwardly along the sides and ends of the strap so as to fix the strap to the hem. The loop portion of the strap which has been formed is indicated at 61 in Fig. 7.

Since the claw 58 is set to receive the spring finger 32 and the pointed guide member 41, the strap will always be properly positioned relative to the claw and in proper alignment with the needle 59. By being able to adjust the guide member 41 rearwardly and forwardly, the folded portion of the loop strap can be properly located beyond the edge of the hem, providing the rear of the claw is aligned with the hem edge. By adjusting the guide member 51 laterally the proper starting point for the needle on the strap can be found. It will be seen that once the adjustment is made of the device, the use of the same when applied to the claw automatically properly locates the loop strap in place under the claw. By an easy withdrawal of the device the loop is held and retained upon the hem by the claw until the sewing operation starts. The claw thus also functions to pull off the formed looped strap from the device.

It will thus be apparent that the loop strap can be easily formed upon the device and then thereafter the device taken and put into the proper location upon the hem whereby the sewing machine claw or foot can be brought down over the looped strap to hold it so that the device can thereafter be pulled outwardly and leave the loop. The loops can accordingly be made up quickly and also the stitching can be effected with accuracy and with the sides inclined at the proper angle so that a uniform loop is made upon the hem each time.

While various changes may be made in the detail construction, it shall be understood that such changes shall be within the spirit and scope of the appended claims.

What is claimed is:

1. A loop forming device on which loops can be formed prior to the placing of the same in position on a hem, comprising a bottom plate having wing portions and

oppositely inclined edges and a tapered portion extending forwardly of the wing portions, a spring finger extending longitudinally of the plate and its end lying over the tapered portion, means for securing the spring finger to the bottom plate, said spring finger securing means including a transversely extending block piece secured to the bottom plate, an angle piece connected to the bottom piece for transverse adjustment relative thereto, a pointed guide member adapted for guiding engagement with a sewing machine claw and extending outwardly over the spring finger, said pointed guide member being adjustably connected to the angle piece for longitudinal adjustment thereof with respect to said angle piece, said angle piece being adjustably connected to the block piece for transverse adjustment along the bottom plate.

2. A loop forming device on which loops can be formed prior to the placing of the same in position on a hem, comprising a bottom plate having wing portions and oppositely inclined edges and a tapered portion extending forwardly of the wing portions, a spring finger extending longitudinally of the plate and its end lying over the tapered portion, means for securing the spring finger to the bottom plate, said spring finger securing means including a transversely extending block piece secured to the bottom plate, an angle piece connected to the block piece for transverse adjustment relative thereto, a pointed guide member adapted for guiding engagement with a sewing machine claw and extending outwardly over the spring finger, said angle piece being adjustably connected to the block piece for longitudinal adjustment along the bottom plate and said pointed guide member being adjustably connected to the angle piece, and said angle piece having longitudinally extending parallel slots and screws extending through the slots and into the block piece and said pointed guide member having spaced horizontal portions with longitudinal slots therein and screws extending into the longitudinal slots and into the angle piece.
